UNITED STATES PATENT OFFICE.

FREDERICK C. HOLTZ, OF SPRINGFIELD, ILLINOIS, ASSIGNOR TO SANGAMO ELECTRIC COMPANY, OF SPRINGFIELD, ILLINOIS, A CORPORATION OF ILLINOIS.

ELECTRIC CLOCK.

Application filed November 15, 1924. Serial No. 750,202.

My invention relates to clocks, and particularly to clocks in which in lieu of the usual main spring an electric motor is employed as the source of power for driving the time train. 5 It has for its objects to obtain the maximum in simplicity of construction whereby liability to derangement is reduced to a minimum; to provide improved means for driving the time train of the clock such as to 10 render it practicable to retain, as far as possible, the highly developed construction of a modern clock movement, and with but slight alteration to drive the same electrically, whereby it will require but little or no 15 attention for long periods of time; and, besides, to so design the mechanism that it will be compact; that a constant driving torque will be exerted, thereby greatly improving the time keeping qualities of the clock, and 20 that all electrical contact devices will be eliminated and the electrical energy consumption be reduced to a minimum. I accomplish these objects as illustrated in the drawings and as hereinafter described. 25 What I regard as new is set forth in the claims.

In the accompanying drawings,—

Fig. 1 is a top or plan view of my improved clock, the case being omitted; 30 Fig. 2 is a side view, partly in vertical section on line 2—2 of Fig. 1;

Fig. 3 is a modified perspective view illustrating the relative arrangement of the clock movement and the driving mechanism therefore, some parts being omitted for the sake of clearness; 35

Fig. 4 is a side view of the rotor element of the motor by which the clock is driven, some parts being in section; and

Fig. 5 is a cross-section on line 5—5 of Fig. 4.

Referring to the drawings,—6 indicates generally a clock movement of any suitable description, but having no main spring for furnishing driving power. It is, however, provided with the usual balance wheel 7 and regulator 8, as shown in Fig. 3, and with a dial 9 and hour and minute hands 10, 11. The clock movement 6 is preferably mounted 45 between pillar plates 12, 13, as shown in Figs. 1 and 2, and is housed in a suitable case which encloses all the operating parts.

For driving the time train of the clock, I provide a small induction motor, the stator

of which comprises a single phase bipolar laminated field magnet, indicated as a whole by the reference numeral 14, on which is mounted a coil 15 which constitutes the primary winding of the motor and is to be connected through its terminals 15^a, 15^b to an alternating source of current supply. The poles 16, 17 of the field magnet 14 have their opposite faces curved so that a cylindrical opening is provided between them in which is rotatably mounted the armature or rotor 18 of the motor. Said rotor comprises a magnetic core member made up of a plurality of laminations 19, and a squirrel cage winding thereon consisting of bars 20 and end plates 21, 22, which plates serve as end rings for the squirrel cage. The squirrel cage is preferably made of copper, and, as best shown in Fig. 4, the bars 20 are obliquely disposed, the latter arrangement being employed to give uniform starting 75 torque, and thereby avoid a pulsating effect on the balance wheel spring. The ends of the bars 20 are preferably upset after the parts of the rotor are assembled, as illustrated in Fig. 4, so that they serve to securely hold the laminations together. While I prefer to use a laminated rotor, it is not essential that it be laminated, as a solid structure for many purposes will function 80 equally well.

The rotor is mounted on a suitable shaft 23 to rotate therewith, said shaft being also provided with a pinion 24, and with pivot pins 25, 26 at its ends by means of which it may be rotatably supported in the manner 85 hereinafter described.

As shown in Figs. 1 and 3, the field magnet poles 16, 17 are provided with shading coils 27, 28 mounted on the pole tips in the manner well known to those familiar with the art, which shading coils serve to change the pulsating flux of the field into a so-called shifting or substantially rotating magnetic field in the cylindrical space between the opposite poles of the field magnet.

As best shown in Fig. 1, the field magnet 14 is mounted between two inverted U-shaped yokes 29, 30, the intermediate portions of which are bent outwardly to accommodate the shading coils 27, 28. In the 105 intermediate portion of the yoke 29 is mounted a bearing plug 31 fitted in a threaded opening so that it may be adjusted end-

wise. Said plug is provided at its inner end with a socket to receive the pivot pin 26 of the rotor shaft 23, as best shown in Fig. 2. A lock nut 32 screwed upon the inner end 5 of said bearing plug holds it securely in its different positions of adjustment. As shown in Fig. 2, the intermediate portion of the yoke 30 is provided with an opening 33 large enough to permit of the free passage 10 therethrough of the pinion 24, and the pivot pin 25 of the rotor shaft 23 is fitted in a suitable bearing in a U-shaped bracket 34 which is secured by screws 35 to the yoke 30, as best shown in Fig. 1. The intermediate 15 portion of said bracket preferably lies close to the pillar plate 13, as shown in Fig. 1, but is not connected therewith. Extending between the intermediate portions of the yoke 30 and bracket 34, and journaled in 20 suitable bearings in said members, is a staff 36 which carries a gear 37 meshing with the pinion 24. Said staff also carries a pinion 38 which forms a driving connection with the clock movement, as will be hereinafter 25 explained.

The motor and the connection above described are supported upon the pillar plate 13 by means of a bracket 39 which is firmly secured to the field magnet 14 by 30 screws 40 which pass through one end portion of the yokes 29, 30 and screw into the bracket 39, thereby binding said parts tightly together. The bracket 39 is in turn secured by screws 41 to a lug 42 carried by the 35 pillar plate 13, as shown in Fig. 1.

The clock movement is driven from the motor through the pinion 38, which meshes with a gear 43 carried by a staff 44 that extends through the pillar plate 13 and 40 carries a pinion 45 that connects with the time train of the clock in any way suitable to impart to the clock mechanism the torque necessary to keep the balance staff, or the pendulum, in a constant state of oscillation. 45 As the specific manner in which this is accomplished has nothing to do with my invention I have not thought it necessary to illustrate any special arrangement for that purpose. The opposite end of the staff 44 50 is journaled in a suitable bearing in an angle bracket 46 secured to the pillar plate 13 by a screw 47, as shown in Fig. 2. The position of these parts is such that the gear 43 is always held properly in mesh with the pinion 38, but obviously the motor with the connections carried by the frame parts thereof, comprising the yokes 29, 30 and brackets 34, 39, may be removed as a unit without disturbing the gear 43, by simply removing 55 the screws 41.

From the foregoing description it will be understood that when current is supplied to the motor the rotation of the rotor shaft 23 will be transmitted through the speed 60 reducing gearing comprising the pinion 24,

gear 37, pinion 38, and gear 43 to the staff 44 through which the time train of the clock is driven, and consequently such time train will be set in motion. The speed reducing gearing between the rotor shaft and the 70 clock mechanism is preferably so designed that the desired torque will be imparted to the staff 44 with the motor armature revolving at a comparatively low speed. While I have shown and described the use 75 of a small alternating current motor, it will be quite evident to those skilled in the art that a small direct current motor operating under similar principles could be used and comes within the scope of my invention. 80

Many advantages are realized by my improved construction, among the most important of which are the omission of the main spring with consequent relief from the necessity of winding the clock; freedom from mechanical difficulties and troubles owing to the fact that there are no contacts and there is nothing to get out of order; the elimination of noise, and freedom from the necessity of lubrication, since the rotating 90 parts move so slowly that they wear indefinitely. The motor described may be attached to any suitable source of alternating current circuit from a conveniently located fixture or socket, and as long as the current 95 supply is maintained the clock will operate without its being given any attention.

What I claim as my invention and desire to secure by Letters Patent, is—

1. In an electric driving device for clocks, the combination of an electric motor having an extending motor shaft, a U-shaped bracket projecting from said motor and having a bearing at its end for receiving the extending end of said motor shaft, a pinion on said motor shaft, a staff journaled in said bracket, a spur gear on said staff meshing with said pinion, and a pinion on said staff adapted to transmit a slow speed drive to the 100 clock.

2. In an electric driving device for clocks, the combination of an electric motor having an extending motor shaft, a yoke secured to said motor, a U-shaped bracket extending outwardly from the side of said motor and having a bearing at its end for receiving the extending end of said motor shaft, a pinion on said shaft, a staff journaled in said yoke and in said bracket, a spur gear on said staff meshing with the pinion on said motor shaft, and a pinion on said staff adapted to transmit a slow speed drive to the 105 clock.

3. In an electric driving device for clocks, the combination of an electric motor comprising a bipolar field magnet, and a rotor 110 mounted to rotate between the poles thereof, a shaft for said rotor; a pair of yokes secured to opposite sides of said field magnet, bearing means in one of said yokes for supporting one end of said rotor shaft, a U- 115

- shaped bracket extending laterally from said motor and having a bearing at its end for receiving the other end of said rotor shaft, a pinion on said shaft, a staff journaled between said bracket and one of said yokes, a spur gear on said staff meshing with said pinion, and a pinion on said staff adapted to transmit a slow speed drive to the clock.
- 5 10 4. In an electric driving device for clocks, the combination of an electric motor comprising a bipolar field magnet and a rotor mounted to rotate between the poles thereof, a shaft for said rotor, a pair of yokes secured to opposite sides of said field magnet, a bearing plug screwing into a threaded opening in one of said yokes and receiving one end of said rotor shaft, a U-shaped bracket extending laterally from said motor, the other end of said rotor shaft being journaled in the end of said bracket, a pinion on said rotor shaft, a staff journaled at one end in the end of said bracket and at the other end in the adjacent yoke, a spur 15 gear on said staff meshing with said pinion, and a pinion on said staff adapted to transmit a driving rotation to the clock.
5. The combination with clock mechanism comprising pillar plates, a clock movement mounted between said pillar plates and a drive staff connected therewith, of an electric driving unit for said clock mechanism comprising an induction motor permanently connected to its source of current supply, bracket means for detachably mounting said unit directly in rear of said pillar plates, said induction motor comprising a rotor shaft extending forwardly toward said clock mechanism, a bearing bracket extending from said motor towards said clock mechanism and affording a bearing support for the end of said rotor shaft, a pinion on said shaft, a staff extending substantially parallel with said rotor shaft and journaled in said bracket, a spur gear on said staff meshing with said pinion, and a pinion on said latter staff adapted to transmit driving rotation to a spur gear on the drive staff of said clock mechanism.
